ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY

SEWING MACHINE LOOPER MECHANISM

Application filed October 29, 1931. Serial No. 571,703.

This invention relates to sewing machines more particularly of the chain-stitch type having a thread-carrying looper which cooperates with a reciprocating needle to produce the well known two-thread chain-stitch.

The invention has for an object to provide an improved looper-actuating mechanism adapted more particularly for cylinder-bed sewing machines in which the work is fed across the cylinder and across or transverse to the blade of the looper. Another object of the invention is to provide for the manual retraction of the looper to a position facilitating the threading of the same; the thread-eye at the free end of the looper being retractile well beyond the edge of the sewing machine throat-plate so that the under thread may be easily inserted therein.

With the above and other objects in view, as will hereinafter appear, the invention comprises the devices, combinations and arrangements of parts hereinafter set forth and illustrated in the accompanying drawing of a preferred embodiment of the invention from which the several features of the invention and the advantages attained thereby will be readily understood by those skilled in the art.

Fig. 1 of the drawing is a longitudinal vertical section through the cylinder-bed of a sewing machine embodying the invention. Fig. 2 is a transverse vertical section through the cylinder-bed showing the looper mechanism and the manually operated looper-retracting rock-shaft journaled in the sewing machine standard. Fig. 3 is a view of certain elements of the looper-actuating linkage in the two extreme positions attained during each stitch-forming cycle while the machine is in normal sewing operation. Fig. 4 is a perspective view of one of the rocker-arms of the looper-driving mechanism. Fig. 5 is an elevation of the primary looper-actuating pitman. Fig. 6 is an elevation of the manually operated lever which is mounted upon and exteriorly to the sewing machine standard for retraction of the looper to threading position. Fig. 7 is a section on the line 7—7, Fig. 2, and Fig. 8 is a perspective view of the lever shown in Fig. 6.

The frame of the machine includes the usual hollow standard 1 and hollow cylinder-bed 2. The main-shaft 3 extends within and longitudinally of the cylinder-bed 2. The machine has the usual reciprocating needle-bar 4 carrying the needles 5. It also has the usual throat-plate 34 and feed-dog 7 arranged to feed the work across the cylinder-bed 2.

Cooperating with the needles 5 is the thread-carrying looper 8 which is mounted on the looper-carrier 9 fulcrumed on the pin 10 carried by the head-block 11 of the looper-supporting rock-shaft 12 journaled in the cylinder-bed 2 and oscillated by the fork-connection 13 with the eccentric 14 on the main-shaft; this connection imparting the usual side-throw or "needle-avoiding" movements to the looper 8.

The looper-carrier 9 has a ball-stud 15 which is connected by the long link 16 to the ball-stud 17 on the rocker-arm 18 fulcrumed on the cross-pin 19 in the cylinder-bed 2. The rocker-arm 18 is connected by a short link 20 to a second rocker-arm 21 which is clamped to the sleeve 22 journaled to rock on the intermediate eccentric portion 23 of a manually operated rock-shaft 24, 24' journaled in the alined bearings 25, 25' in the standard 1. There is fixed to the rock-shaft 24 section 24 a handle 26 by means of which the intermediate eccentric portion 23 may be rocked from full line to dotted line position, Fig. 1, corresponding to a shift of the handle 26 from full line to dotted line position, Fig. 6. The sleeve 22 carries a ball-ended arm 27 which is connected by the pitman 28 to the crank-strap 29 embracing the crank 30 on the main-shaft 3.

When the parts are in normal operative or sewing relation, the handle 26 is in full line position, Fig. 6, and the eccentric portion 23 of the manually operated rock-shaft 24 is in full line position, Figs. 1 and 3. While the machine is in sewing operation, the rocker-arms 21 and 18 oscillate between the extreme positions shown in Fig. 3 and it will be observed that the link 20 and rocker-arm 21 constitute a toggle-device and approach alignment in the dotted line position of the

parts, Fig. 3, when the looper 8 is at the end of its loop-seizing or advancing stroke. This approach to alinement of the link 20 and rocker-arm 21 slows up the advancing movement of the looper after the latter has seized the needle-loops and enables a comparatively short-stroke looper to be used while retaining a rapid loop-seizing and loop-shedding action. The rock-shaft 24 is detained in its 10 normal sewing position by the spring-pressed 70
detent 31 the conical ended head 32 of which enters a V-shaped groove 33 in the rock-shaft 24.

When it is desired to thread the looper, the 15 machine is stopped with the looper in retracted position, as shown in full lines, Fig. 1. The operator then shifts the handle 26 from full to dotted line position, Fig. 6, thereby 75
rocking the shaft 24, 24' and shifting the 20 intermediate eccentric portion 23 to dotted 80
line position, Fig. 1. This manually operated movement of the eccentric 23 causes the 85
rocker-arms 21, 18 and link 20 to move to dotted 90
line position, Fig. 1, thereby retracting 95
the looper 8 to dotted line position where- 100
in the looper-eye 8' is carried well out from 105
under the throat-plate 34 and is readily 110
accessible for threading purposes. During 115
this manual shift of the parts the link 20
and rocker-arm 18 approach alinement and 120
constitute a second and reversely acting toggle-device which has the effect of increasing 125
the retracting movement imparted to the link 16 and looper-carrier 9, as is desirable to 130
carry the looper-eye 8' well to one side and 135
out from under the throat-plate. After the 140
looper has been threaded the handle is re- 145
turned to full line position, Fig. 6, and the 150
parts shown in dotted lines in Fig. 1 are 155
returned to their full line or normal sewing 160
positions. The inner face of the handle 26 is 165
provided with an undercut arcuate slot 35 170
which is entered by the screw-pin or stop 36 175
projecting from the standard 1.

45 Having thus set forth the nature of the invention, what I claim herein is:—

1. Looper mechanism for sewing machines 180
having, in combination, a thread-carrying 185
looper, driving means for imparting advanc- 190
ing and retracting movements to said looper 195
in the formation of stitches, manually operat- 200
ed means for retracting the looper to a pos- 205
tion facilitating threading thereof, said driv- 210
ing and manually operated means including a 215
pair of rocker-arms and a link connecting 220
said arms, said link and rocker-arms being so 225
relatively related that said link approaches 230
alinement with one of said rocker-arms dur- 235
ing each stitch-forming cycle as the looper ap- 240
proaches the end of its advancing stroke, and 245
approaches alinement with the other rocker- 250
arm during the manual retraction of the loop- 255
er to threading position.

2. Looper mechanism for sewing machines 260
having, in combination, a thread-carrying 265

looper, means for imparting loop-seizing 270
movements to said looper, said means includ- 275
ing a toggle-device for slowing up the motion 280
of said looper as it nears the end of its loop- 285
seizing stroke, and manually operated means 290
for retracting said looper to a position for 295
convenience in threading, said means includ- 300
ing another toggle-device for increasing the 305
retracting motion manually imparted to the 310
looper, said toggle-devices having a link in 315
common.

3. In a sewing machine, the combination 320
with a reciprocating needle and a main-shaft, 325
of a looper, means for imparting side-throw 330
movements to said looper, and means for im- 335
parting loop-seizing and -shedding move- 340
ments to said looper, said last mentioned 345
means including a rocker-arm spaced from 350
said looper, a link-connection between said 355
rocker-arm and looper, a second rocker-arm, 360
a manually operated eccentric fulcrum sup- 365
port therefor, a link-connection between said 370
rocker-arms, a crank on said main-shaft, and 375
a pitman connection between said crank and 380
second-mentioned rocker-arm. 385

4. In a sewing machine, a frame including 390
a supporting standard and a hollow cylinder- 395
bed, a reciprocating needle, a main-shaft, a 400
thread-carrying looper-blade mounted with- 405
in the free end of said cylinder-bed and hav- 410
ing endwise advancing-and-retracting loop- 415
seizing and -shedding movements lengthwise 420
of the cylinder-bed, means connected to the 425
main-shaft within said standard for impart- 430
ing said loop-seizing and -shedding move- 435
ments to the looper-blade and manually op- 440
erated means mounted in and accessible exte- 445
riorly of said standard for retracting said 450
looper-blade lengthwise of itself and toward 455
said standard and beyond its normal opera- 460
tive retracted position in sewing, for con- 465
venience in threading. 470

In testimony whereof I have signed my 475
name to this specification.
